S. WAGNER

WOOD BORING MACHINE

Filed June 22, 1925

INVENTOR.
STEFAN WAGNER

BY *B. J. Craig*

ATTORNEY.

UNITED STATES PATENT OFFICE.

STEFAN WAGNER, OF LOS ANGELES, CALIFORNIA.

WOOD-BORING MACHINE.

Application filed June 22, 1925. Serial No. 38,652.

To all whom it may concern:

Be it known that I, STEFAN WAGNER, a citizen of the United States, residing at Los Angeles, in the county of Los Angeles 5 and State of California, have invented a certain new and useful Improvement in Wood-Boring Machines, of which the following is a full, clear, and exact description, reference being had to the accompanying drawings.

This invention relates to boring machines.

The general object of the invention is to provide an improved boring machine wherein in novel means is arranged for simultaneously boring a plurality of holes.

A further object of the invention is to provide a boring machine wherein a plurality of chucks are arranged for movement toward and from each other and wherein 20 the chucks may be moved without affecting the means for operating the chucks.

Another object of the invention is to provide an improved boring machine wherein a plurality of chucks are mounted for 25 adjustment relative to each other and wherein the provision is made for adjusting the work relative to the chucks while the chucks are continually in direct driving engagement.

30 Other objects of the invention will be apparent from the following description taken in connection with the accompanying drawings wherein:

Fig. 1 is a perspective view of the boring machine embodying the features of my invention;

Fig. 2 is a sectional view through the casing on line 2—2, Fig. 3, and

40 Fig. 3 is a central longitudinal sectional view showing the operating mechanism.

Referring to the drawing by reference characters, I have shown my invention as embodied in a machine having a base 10. This base is provided with a slotted guideway 45 which has an inclined outer face 12. Mounted upon the guideway is a bracket 14 which has a work table 15 thereon. This work table is provided with a keyway 16 for the reception of fastening members for 50 holding the work in place. The base 10 is shown as provided with a screw spindle 19 which has at the top a spiral gear 20 which is adapted to mesh with another spiral gear 21. The gear 21 is keyed on a shaft 22 55 which is provided with a lifting crank 23.

The construction is such that when the lifting crank is rotated the work table will be moved up and down relative to the base 10.

Adjacent the top of the slotted guideway 11 I show a transverse slotted guideway 60 having inclined side faces 25 thereon in which a slide 26 having inclined edges 27 is mounted for movement. This slide 27 is provided with a rack 28 upon its lower face which is in engagement with a segmental gear 29 which is mounted on a shaft 30 for rocking movement. The segmental gear 29 is connected by means of a link 31 with a lever 32 which is pivoted on a shaft 33 secured to the base 10. Upon the lever 70 32 a foot pedal 35 is adjustably mounted by means of bolts 36 which may be fitted in apertures 27 to change the leverage when desired.

Mounted upon the slide 26 I show a 75 gear case 40 which includes a base 41 having front and back plates 42 and 43. A top plate 44 includes end portions 45 to which the front and back plates 42 and 43 are secured by bolts or in any other desired manner. The end portions 45 are provided with suitable bearings 46 for the reception of the shaft 47 of a spiral gear 48 which extends substantially the full length of the gear case 40. The spiral gear 48 is 85 in mesh with a spiral gear 49, the shaft 50 of which is supported in bearings 50' arranged in the front and back plates 42 and 43.

Mounted upon the slide 26 I show an electric motor 51, the armature shaft 52 of which is connected by means of a universal coupling 53 with the shaft 50 of the gear 49 previously described. When the motor 51 operates it will be apparent that the gear 95 49 will be driven and will drive the spiral gear 48.

Extending across the gear case 40 I show a shaft 60 which is suitably supported in bearings 61 and has a crank 62 thereon for 100 turning it. This shaft is provided with two sets of threads 63 and 64 the pitch of which is reversely directed as shown in Fig. 3 and these portions 63 and 64 are provided with nuts 65 and 66 which have projecting 105 wings 67. These wings 67 are slotted as at 68 to fit over elongated rails 69 on the interior of the front and back of the casing.

From the foregoing description it will be apparent that if the crank 62 is turned the 110

nuts 65 and 66 will move along the tongues 69 depending on the direction in which this crank is rotated. The wings 67 are projected upwardly to provide a U-shaped support 5 for the bearings 71 in which the shafts of chucks 72 are arranged. The shaft of each chuck 72 is provided with a spiral gear 73 which meshes with the spiral gear 48 previously described.

10 The slide 26 is provided with a projection 75 thereon which is threaded to receive a threaded stop member 76 which is provided with a lock nut 77. The stop member 76 is adapted to engage the rear part of 15 the base 10 to limit the forward movement of the boring tools 80 arranged in the chucks 72.

From the foregoing description it will be apparent that by rotating the crank 62 the 20 position of the chucks 72 and consequently the position of the boring tools 80 can be adjusted, and that by adjusting the stop member 76 the depth of the cut may also be 25 adjusted so that in operation a plurality of holes can be accurately bored at a desired distance apart. It will also be observed that the adjustment of the chucks may be effected while they are rotating. This action enables 30 elongated slots to be cut in the work since by using proper tools in the chucks a cylindrical hole can be cut after which the crank 62 can be turned to move the tool laterally in the hole to cut the slots. A rule 35 81 may be fixed on the front 42 and the chuck beneath this rule may have an index thereon to indicate the position of the chuck.

The machine embodying the features of 40 my invention is easily made, it can be economically manufactured and is not likely to get out of order.

Having thus described my invention, I claim:

1. In a boring machine, a base having a 45 slide movable thereon, a pair of chucks supported on said slide, a shaft for each chuck, a gear on each of said shafts, an elongated gear engaging both of said first mentioned gears for simultaneously driving both of said chucks, means to move said chucks toward and from each other along said elongated gear while said elongated gear and said chuck gears remain in engagement.

2. In a boring machine, a base having a 50 work table thereon, a pair of chucks mounted for movement relative to said work table, means to mount said chucks for movement toward and from one another, said means including a member having right and left 55 handed threads thereon, and means to drive said chucks, said driving means including a gear on said chucks and a single gear for driving the chuck gears, said driving means

being operative while the chucks are being moved toward and from each other.

3. In a boring machine, a base having a 60 member movable thereon, a plurality of chucks supported on said member for movement relative to each other, elongated driving means for said chucks, driven means on the chucks engaging the driving means, means for simultaneously moving said chucks toward and from each other while the driving and driven means are in engagement, said means including a member having right and left handed threads therein, 65 and said chucks having blocks thereon engaging said right and left handed portions of the member.

4. In a boring machine, a base, a slide 70 movable on said base, means to move said slide, a case on said slide, a pair of chucks supported in said case, a shaft for each chuck, a gear on each of said shafts, an elongated gear engaging and driving both 75 of said first mentioned gears to simultaneously drive both of said chucks, said first mentioned gears being movable along the elongated gear while in mesh therewith, means to move said first mentioned gear and the chucks along said elongated gear, a third gear 80 engaging said elongated gear, a motor, a shaft on said motor, a shaft on said third gear, a universal coupling connecting said last mentioned shaft and said motor shaft, said motor being mounted on said slide and means to limit the movement of said slide 85 in one direction.

5. In a boring machine, a base having a 90 guideway thereon, a slide movable in said guideway, a rack mounted on said slide, a toothed segment engaging said rack, a pivoted operating pedal, a link connecting 95 said pedal and said segment, a pair of chucks supported on said slide, a shaft for each 100 chuck, a spiral gear on each of said shafts, a case adjacent said chucks, a spiral gear engaging both of said first mentioned gears for simultaneously driving both of said 105 chucks, nuts connected to said chucks, a threaded member engaging said nuts, means for operating said threaded member for moving said chucks a third gear engaging 110 said second mentioned gear, a motor on said slide, a shaft on said motor, a shaft on said third gear, a universal coupling connecting 115 said last mentioned shaft and said motor shaft on said slide, means to limit the movement of said slide in one direction, a work table and means to move said table relative 120 to said slide.

In testimony whereof, I hereunto affix my signature.

STEFAN WAGNER.
